(57) **CLAIM**

The ornamental design for a pouch for retrieved waste toner, as shown and described.

DESCRIPTION

FIG. 1 is a front, top, let side perspective view of a pouch for retrieved waste toner showing our new design;

FIG. 2 is a front elevational view thereof, shown at a reduced scale;

FIG. 3 is a rear elevational view thereof;

FIG. 4 is a left side elevational view thereof, shown at an enlarged scale;

FIG. 5 is a right side elevational view thereof;

FIG. 6 is a top plan view thereof, shown at a reduced scale;

FIG. 7 is a bottom plan view thereof;

FIG. 8 is a second perspective view thereof, shown at an enlarged scale and in an alternate position of use; and,

FIG. 9 is a third perspective view thereof, shown in a third position of use.

The broken lines depict environmental subject matter only and form no part of the claimed design.
